UNITED STATES PATENT OFFICE.

ROBERT BREYER, OF MILWAUKEE, WISCONSIN, ASSIGNOR TO PHOENIX HOSIERY COMPANY, OF MILWAUKEE, WISCONSIN, A CORPORATION OF WISCONSIN.

DESIGN FOR A STOCKING.

Application filed January 3, 1927. Serial No. 20,266. Term of patent 14 years.

To all whom it may concern:

Be it known that I, ROBERT BREYER, a citizen of the United States, and a resident of Milwaukee, county of Milwaukee, State of Wisconsin, have invented a new, original, and ornamental Design for a Stocking, of which the following is a specification, reference being had to the accompanying drawing, forming a part thereof.

In the drawings:

The design comprises a decoration above the heel characterized by a pair of upwardly extending straight long stripes inclined towards each other and towards the rear seam and forming a hollow triangle.

I claim:—

The ornamental design for a stocking as shown and described.

ROBERT BREYER.
